DESIGN FOR A FOUNTAIN BRUSH

James H. Johnson, Indianapolis, Ind.

Application January 31, 1934, Serial No. 50,567

Term of patent 14 years

To all whom it may concern:

Be it known that I, JAMES H. JOHNSON, a citizen of the United States, residing at Indianapolis, in the county of Marion, have invented a new, original, and ornamental Design for a Fountain Brush, of which the following is a specification, reference being had to the accompanying drawing, forming part thereof.

In the drawing, Fig. 1 is a side elevation of a fountain brush, showing my new design; Fig. 2 is a top plan view, and Fig. 3 is a front elevation thereof.

I claim:

The ornamental design for a fountain brush, as shown.

JAMES H. JOHNSON.
